UNITED STATES PATENT OFFICE.

WILLIAM F. WACKER, OF SIOUX CITY, IOWA.

BELL-RINGING APPARATUS.

1,091,902.

Specification of Letters Patent. Patented Mar. 31, 1914.

Application filed August 25, 1913. Serial No. 786,524.

To all whom it may concern:

Be it known that I, WILLIAM F. WACKER, a citizen of the United States of America, residing at Sioux City, in the county of 5 Woodbury and State of Iowa, have invented certain new and useful Improvements in Bell-Ringing Apparatus, of which the following is a specification.

My invention relates to improvements in 10 bell ringing and bell tolling apparatus, and relates more particularly to mechanism for this purpose by means of which the operations are controlled by electrical circuits.

Among the objects of my invention are: 15 (1) To provide a structure for this purpose by means of which a pivotally mounted bell may be oscillated at will by the use of a motor, the mechanism providing for the starting of the motor prior to the bringing of the bell shaft into operation, thereby reducing the load stress on the motor in starting the oscillating movements of the bell. (2) To provide circuit connections and apparatus 20 therein by means of which the connections between the motor and the bell shaft can be brought into operative engagement at will and while one of the members of the connections is moving and the bell stationary. (3) To provide apparatus embodying a plurality of bells, at least one of which is adapted 25 to be connected directly to the motor at will, the remaining bell or bells being mounted to permit engagement with the bell shaft at will, thereby providing for the ringing of 30 one or more of a plurality of bells from a single motor at the will of the operator. (4) To provide an arrangement for the tolling 35 of bells in which the tolling hammer is operated by means of an electrical circuit.

40 Other and further objects of the invention are to provide a structure which is simple and efficient in operation, durable in construction, readily installed, and which can be manufactured at a relatively low cost.

45 To this and other ends, the nature of which will be readily understood as the invention is hereinafter disclosed, my invention consists in the improved construction and combination of parts hereinafter fully 50 described and illustrated in the accompanying drawings, and more particularly pointed out in the appended claims.

In the accompanying drawings, in which 55 similar reference characters indicate similar parts in each of the views, Figure 1 is a view in front elevation and partly in sec-

tion showing apparatus adapted to meet the terms of my invention. Fig. 2 is a cross sectional view of parts shown in Fig. 1, portions of the apparatus being shown in elevation. Fig. 3 is a detail view partly in section and partly in elevation showing a modification the general arrangement of apparatus being that employed in the bell tolling operation.

60 10 designates the supports for the bell shaft, the supports being suitably mounted and of any usual type.

11 designates the main bell shaft, which 65 may be provided with a wheel 12 operated by means of a rope 13, this bell shaft being of the well known type in which there is an arched portion from which the bell is supported, the bell being of the type adapted to be oscillated to cause it to be sounded in a 70 manner provided generally for what are known as church bells, or those which are of considerable weight and therefore requiring unusual power in overcoming the inertia in the starting operation. In the 75 present instance, the shaft 11 is lengthened, as at 11^a, and swiveled on the extended portion is a member 14, adapted to be oscillated by the rotation of a motor 20, the latter being connected with a crank arm 14^a of the 80 member 14 by a crank 16, the arrangement 85 preferably being such that connection of the crank 16 may be made with the crank arm 14^a at any one of a plurality of points, thus varying the throw of the crank arm and 90 consequently varying the amount of oscillation of the bell, the drawings showing the use of a plurality of openings 14^b, either one 95 of which may be used in connecting the crank to the crank arm.

The member 14 is preferably weighted below the shaft and opposite the crank arm 14^a, any suitable construction for this purpose being provided, a preferred form being to employ a hollow casing 14^c in which a 100 weighted member 14^d is mounted to move lengthwise of the casing, said member 14^d having a stem 14^e adapted to extend through a movable cap 14^f which acts as a closure for the outer end of the casing. In operation, it is intended that this member 14 be brought into operation prior to beginning the movements of the bell shaft, thus enabling the load on the motor to be less than the load provided by the bell itself, the bell 110 shaft being adapted to be connected to the member 14 after the latter has reached its

speed. Various ways may be provided for connecting the bell shaft to the member, a preferred form being shown in the drawings, in which the bell shaft is provided with a radial recess 11^b leading toward the bottom of the shaft when the bell is in normal position, said recess being adapted to receive a pin 14^e carried by the inner end of the bell 14^a, said member 14^a being moved inwardly so that when the pin 14^e is opposite the recess 11^b, the pin will enter the recess and thus connect the moving member 14 to the shaft 11 and start the bell-ringing operation. A preferred form of mechanism for providing this movement of the member 14^a at will is shown in Fig. 1, comprising an arm 15 mounted on the side of the casing 14^c and projecting therethrough into an opening 14^h of the member 14^a, said arm being adapted to be oscillated by electrical means through connections 15^a and 15^b, the latter of which may act as the armature for an electro-magnet 16 mounted on an arm 14ⁱ projecting from the casing 14^c, the connections being such that when the magnet 16 is energized by the completion of an electric circuit therethrough from a source of electrical supply such as a battery 17, the armature 15^b will be attracted and thus move the member 14^a in a direction to carry its pin 14^e toward the shaft. Inasmuch as the member 14 is assumed to be swinging when this operation takes place, it will be readily understood that when the pin 14^e is opposite the recess 11^b, the full effect of the electrical action will be had causing the pin 14^e to enter the recess, the pin having a tapered end to facilitate this action.

Obviously a suitable switch arrangement indicated diagrammatically at 17 may be mounted within the circuit to enable the magnet 16 to be energized at will by closing the circuit, it being readily understood that when the circuit is broken by the opening of the switch 17, the weight of the member 14^a will cause the pin 14^e to become disengaged from the recess 11^b and thus break the operative connection between the motor and the bell, leaving the bell to pass to its normal position in the usual manner and without affecting the motor, the load stress on the latter being reduced to that of the member 14 which, being positively connected to the motor, operates concurrently with the motor and consequently has its stopping action controlled by that of the motor; being however, of a greatly decreased weight when compared to the weight of the bell, any injurious effect on the motor is greatly reduced if not eliminated.

As shown in Fig. 2, the motor 20 may be of the electrical type, being operated by a suitable circuit 20^a including a switch 20^b, the circuit being provided with a suitable 65 source of supply, indicated diagrammati-

cally as a battery 20^c. This provides for the ready control of the operation of the motor at a distance from the bell tower or belfry, the motor being located in juxtaposition to the bell while the controlling switch may be located at any desired point.

It will be readily understood that when it is desired to ring the bell, a closing of the switch 20^b will start the motor 20, the movement of which will cause the member 14 to oscillate on the bell shaft as heretofore described, and when the motor and member 14 have reached the desired speed, the switch 17 is closed which provides the operation of connecting the oscillating member 14 with the bell shaft which is stationary, thus causing the bell shaft to move in unison with the member 14 and provide the ringing operation. By reason of the weight of the member 14, its momentum will have an important action in overcoming the inertia of the bell shaft and act somewhat in the nature of a buffer between the bell shaft and the motor at the time the shaft becomes connected to the motor through the connections.

The construction above described comprises the main features employed and, where but a single bell is to be rung, completes the apparatus. Where it is desired, however, to operate a larger number of bells, such for instance as a series of bells which are adapted to produce a harmonic chord, and are to be used in conjunction with the main bell, the additional bells may be connected up to the bell shaft 11 and thus provide for synchronous action of all the bells. One form in which this connection may be provided is shown in Fig. 1, in which 18 designates a second bell shaft, said shaft carrying a bell and also carrying a coupling member 19 adapted to coöperate with a complementary member 21 carried by the shaft extension 11^a, said coupling member being adapted to be moved into engagement with the member 19 by suitable means such as an arm 22 acting as an armature for a magnet 23 mounted in a circuit 24, the latter including a switch 24^a.

When the circuit is closed through the switch 24^a, the armature 22 will be attracted by the magnet 23 and thus cause the clutch members to operatively engage and couple the two shafts 11 and 18 together for similar movement. A spring 22^a may act as the means for releasing the clutch engagement when the circuit is broken at the switch 24^a. Obviously, the shaft 18 may carry but a single bell or a plurality of bells, and if desired, may in itself act as the power shaft for additional bell shafts, it being readily understood that the arrangement provided by the coupling of the shafts 11 and 18 may be employed in coupling shaft 18 with another shaft, etc., this latter permitting of successively increasing the number of bells 130

which may be connected together to operate. It will be understood, however, that in the construction shown, the main bell, indicated at 25, will necessarily ring whenever the 5 member 14 is connected so as to operate any bell, the additional bells being connected either *en bloc* by being mounted so as to operate in synchronism with a single shaft, or successively where coupling devices are employed and the bells are to be connected up in operation successively.

The bell tolling structure shown in Fig. 3 comprises a hammer or tapper 30 carried by an arm 31, said hammer or tapper acting as 15 the armature to a magnet 32 mounted in a circuit 33 which includes a switch 34, the hammer or tapper being normally retracted by a spring 35. It will be readily understood that by alternately opening and closing 20 the circuit 33 through the switch 34, the hammer or tapper will be actuated to provide a succession of single bell sounding strokes, and as the rapidity with which the 25 strokes are provided are entirely controlled by the operations of the switch 34 (which may be in the form of a push button), it will be readily understood that the apparatus provides an efficient means for tolling a bell of large size.

30 While I have herein shown and described ways in which my invention may be carried into effect, it will be readily understood that changes and modifications therein may be found necessary or desirable to meet the exigencies of use, and I desire to be understood as reserving the right to make any and all such changes and modifications as may be found necessary or desired in so far as the 35 same falls within the spirit and scope of the 40 invention as expressed in the appended claims.

Having thus described my invention, what I claim as new is:

1. In bell ringing apparatus, the combination 45 with a bell shaft adapted to be oscillated, of an element mounted to oscillate on the shaft, said element being weighted and having a member adapted to engage said shaft at will, and means for oscillating said 50 element.

2. In bell ringing apparatus, the combination 55 with a bell shaft adapted to be oscillated, of an element mounted to oscillate on the shaft, said element being weighted and having a member adapted to engage said shaft at will, and means for oscillating said element, said means including a motor operable at will and positively connected to said element.

60 3. In bell ringing apparatus, the combination with a bell shaft adapted to be oscillated, of an element mounted to oscillate on the shaft, said element being weighted and

having a member adapted to engage said shaft at will, and means for oscillating said 65 element, said means including a motor positively connected to said element and operable at will, the engagement and disengagement of said element, member and shaft being controlled independently of the motor control.

4. In bell ringing apparatus, the combination with a bell shaft adapted to be oscillated, of an element mounted to oscillate on the shaft, and means for oscillating said element, said element comprising a casing having a shiftable weight member, said weight member having a pin adapted to enter a recess in said shaft.

5. In bell ringing apparatus, the combination with a bell shaft adapted to be oscillated, of an element mounted to oscillate on the shaft, means for oscillating said element, said element comprising a casing having a shiftable weight member, said weight member having a pin adapted to enter a recess in said shaft, and means traveling with said casing for shifting said weight member in one direction to provide the engagement of 80 element and shaft at will.

6. In bell ringing apparatus, the combination with a bell shaft adapted to be oscillated, of an element mounted to oscillate on the shaft, means for oscillating said element, said element comprising a casing having a shiftable weight member, said weight member having a pin adapted to enter a recess in said shaft, and means traveling with said casing for shifting said weight member in one direction to provide the engagement of 95 element and shaft at will, the opposite movement of said weight member being provided by the weight of the member upon release of said latter means.

7. In bell ringing apparatus, the combination with a bell shaft adapted to be oscillated, of an element mounted to oscillate on the shaft, means for oscillating said element, said element comprising a casing having a shiftable weight member, said weight member having a pin adapted to enter a recess in said shaft, and means traveling with said casing for shifting said weight member in one direction to provide the engagement of element and shaft at will, said means including an arm, an electric circuit having a magnet, an armature for said magnet and connections between said arm and said armature for moving the weight member to provide engagement when the circuit is closed.

In testimony whereof I hereunto affix my signature in presence of two witnesses.

WILLIAM F. WACKER.
